UNITED STATES PATENT OFFICE.

GARRETT H. RHEUTAN, OF SAN FRANCISCO, CALIFORNIA, ASSIGNOR OF
ONE-HALF TO R. B. LINCOLN, OF WALTHAM, MASSACHUSETTS.

STEAM-GENERATOR.

SPECIFICATION forming part of Letters Patent No. 692,032, dated January 28, 1902.

Application filed October 19, 1901. Serial No. 79,248. (No model.)

To all whom it may concern:

Be it known that I, GARRETT H. RHEUTAN, of San Francisco, in the county of San Francisco and State of California, have invented 5 certain new and useful Improvements in Steam-Generators, of which the following is a specification.

This invention relates to steam boilers or generators of the type set forth in my application for Letters Patent of the United States, filed July 16, 1901, Serial No. 68,507. The boiler set forth in said application comprises an external boiler forming a casing inclosing a fire-space and having outer and inner walls 15 and an internal water-tube portion composed of tubes connected at their ends to portions of the inner wall of the outer boiler, said portions constituting tube-sheets, the said tubes extending inwardly and upwardly from the 20 sides to the top of the fire-space.

The present invention has for its chief object to render the water-tubes of the internal boiler readily accessible, particularly when the boiler is made on a small scale, suitable 25 for automobiles and other relatively small structures.

The invention consists in the improvements which I will now proceed to describe and claim.

30 Of the accompanying drawings, forming a part of this specification, Figure 1 represents an end elevation and partial transverse section of a steam generator or boiler embodying my invention. Fig. 2 represents a side 35 elevation and partial longitudinal section of the same.

The same reference characters indicate the same parts in both figures.

In the drawings, 1 and 2 represent, respectively, the outer and inner walls of the external boiler portion, which is made approximately in the form of an arch, the side portions of which constitute the sides and the top portion the top of a fire-space, which may 45 have at its bottom a grate, or, as here shown, a burner *w*, for hydrocarbon or other fuel, said burner resting on a perforated bottom plate *x*, forming a part of a jacket which encloses the external boiler. The water and 50 steam spaces between the walls 1 and 2 are suitably closed at the ends of said walls, and

said spaces do not extend across the ends of the fire-space. The ends of the arched external boiler are left open or provided with openings, to which are fitted end pieces or 55 covers 3, the margins of which are detachably secured by bolts 4 or other fastening means to the ends of the external boiler. The end pieces or covers 3 may, however, be of any other suitable construction. It will be seen 60 that the open ends of the arched external boiler and the detachably-secured covers closing said ends enable access to be had to the interior of the fire-space and to the hereinafter-described water-tubes therein. 70

The internal water-tube boiler is composed of tubes *d d*, the lower ends of which are inserted in the lower portions of the inner walls 2 of the external boiler, while their upper ends are inserted in the upper portion of said 75 inner wall, as best shown in Fig. 1, the tubes extending inwardly and upwardly from the sides to the top of the fire-space. The portions of the inner wall 2 in which the tubes are inserted constitute tube-sheets, which 80 constitute the inner walls of water and steam drums and are crowned or curved inwardly into the fire-space to increase the capacity and strength of the said water and steam drums. The outer wall 1 of the external 85 boiler is provided with openings 5, which are formed to afford access to the lower tube-sheets, in which the lower ends of the tubes *d* are inserted. To said openings 5 are fitted covers 6, which constitute the outer walls of 90 the water-drums and are detachably secured by bolts 7 to the portions of the external boiler surrounding the openings 5. In the upper portion of the outer wall 1 is an opening 8, which is formed to afford access to the tube-sheet in which the upper ends of the tubes *d* are inserted. To said opening 8 is fitted a cover 9, which constitutes the outer wall of the steam-drum and is secured by bolts 10 to the 95 portions of the external boiler surrounding the opening 8. Said covers 6 and 9 are crowned or curved outwardly to further in-

crease the capacity and strength of the water and steam drums. It will be seen that the openings 5 and 8 and the detachable covers fitted thereto make the tube-sheets readily accessible, so that the operations of inserting and removing the tubes *d* may be very conveniently performed.

q q represent stretches of a sinuous feed-water-conducting pipe interposed between the external boiler and the outer tubes of the internal boiler, said pipe receiving feed-water from a suitable source of supply and conducting it in the directions indicated by the arrows in Fig. 2. There are two of these pipes, one at each side, and each has an extension *q'*, connected with the transverse pipe *q q*, the ends of which communicate with the lower portions of the external boiler. The feed-water is therefore partially heated by the waste heat which has passed through the spaces between the tubes *d*.

g represents the outlets for the products of combustion from the fire-space to the flue 12 in the inclosing jacket, said flue being arranged to conduct the products of combustion away from the jacket to a suitable point of discharge.

13 represents a perforated dry-pipe which extends longitudinally through the steam-drum and conducts the steam therefrom.

I claim—

1. A steam-generator comprising an external boiler forming the sides and top of a casing inclosing a fire-space, the top and the lower side portions of the inner wall of said boiler being perforated to form tube-sheets, the top tube-sheet constituting the inner wall of a steam-drum while the side tube-sheets form the inner walls of two water-drums, bent tubes formed to extend inwardly from said water-drums into the fire-space and upwardly to the steam-drum, said tubes being engaged at their ends with the said tube-sheets and constituting an internal water-tube boiler, the side and top portions of the outer wall of the external boiler being provided with openings formed to afford access to said tube-sheets, and covers fitting said openings and detachably secured to said

outer walls, said covers forming the outer sides of said water and steam drums and by their detachability enabling access to be had to both the upper and the lower ends of the tubes.

2. A steam-generator comprising an external boiler forming the sides and top of a casing inclosing a fire-space, the top and the lower side portions of the inner wall of said boiler being curved inwardly into the fire-space and perforated to form tube-sheets, the top tube-sheet constituting the inner wall of a steam-drum while the side tube-sheets form the inner walls of two water-drums, bent tubes formed to extend inwardly from said water-drums into the fire-space and upwardly to the steam-drum, said tubes being engaged at their ends with the said tube-sheets and constituting an internal water-tube boiler, the side and top portions of the outer wall of the external boiler being provided with openings formed to afford access to said tube-sheets, and covers fitting said openings and detachably secured to said outer walls, said covers being curved outwardly and forming the outer sides of said water and steam drums, the inward curvature of the said tube-sheets and the outward curvature of said covers increasing the capacity and strength of the water and steam drums.

3. A steam-generator comprising an external boiler formed as a casing inclosing a fire-space and having outer and inner walls, an internal water-tube boiler composed of tubes secured at their lower ends to the lower portions of the said inner wall and at their upper ends to the upper portion of the inner wall, and water-conducting pipes located between the external boiler and the tubes of the internal boiler, said pipes being connected in series, each series communicating at one end with a source of feed-water supply, and at the other end with the external boiler.

In testimony whereof I have affixed my signature in presence of two witnesses.

GARRETT H. RHEUTAN.
